UNITED STATES PATENT OFFICE.

CHARLES BILLY, OF PARIS, FRANCE.

APPARATUS FOR GENERATING ACETYLENE.

No. 840,552.

Specification of Letters Patent.

Patented Jan. 8, 1907.

Application filed March 5, 1906. Serial No. 304,419.

To all whom it may concern:

Be it known that I, CHARLES BILLY, a citizen of France, residing at Paris, France, have invented new and useful Improvements in 5 Portable Apparatus for Generating Acetylene, (for which a French patent has been filed December 12, 1905, application actually pending before the French office,) of which the following is a specification.

10 The present invention relates to a portable apparatus for generating acetylene, enabling various improvements pertaining to apparatus of this kind to be carried into effect.

15 The drawing accompanying the present description represents a longitudinal sectional elevation of this apparatus, which comprises the following elements:

1 is a vessel in which the carbid of calcium is placed. It is closed at top by a 20 domed lid or cover 5, which can be rendered air-tight by means of a rubber ring 2, inserted in an appropriate recess or groove 4, into which enters a projecting rim or flange 3, formed on the periphery of the said lid or 25 cover 5, and on the edge of which recess there may be placed a grid or perforated plate 7, the use of which will be hereinafter explained. At top and within the domed lid or cover 5 is a tapped socket 6, into which is screwed a pipe 30 8, up which the water rises, and which pipe passes through the bottom of the vessel 1 and through a suitable socket 11. This tube is provided with a small lateral orifice 9 and terminates at its lower end in a block 10, 35 forming a stopper and abutting against the bottom of the vessel 1, and which by means of a leather or rubber washer 12, interposed between it and the bottom of said vessel 1, constitutes a tight joint. This stopper is 40 provided with a central passage 13, by means of which the interior of this latter is placed in communication with the surrounding space and presents a truncated seat 14, the purpose of which is hereinafter explained. The 45 socket 11 is screw-threaded externally and carries, by means of a tapped ferrule, a perforated tube 15, which is arranged concentrically with the tube 8 and is provided at its upper end with lugs 16, whereby its screwing 50 into place is facilitated. Within this tube 15 is an imperforate tube 16, shorter than the tube 15 and provided at its upper end with a flange 17, by means of which it is supported in place.

55 Above the vessel 1 is a closed space 18, constituting a compression-chamber, the work-

ing of which will be hereinafter described. This chamber is supported on the one hand by a tubular stem 19, forming an extension of the tube 8, and on the other hand by the 60 tubes 20 and 41, both of which serve for the escape of the gas generated in the vessel 1. The tubular stem 19 is screw-threaded near its upper end and serves more particularly for the purpose of guiding the rod 21, (screwed 65 at 22,) which carries at its upper end a milled button or knob 23 and at its lower end a cylindro-conical enlargement 24, which by being applied to or removed from the seat 14 permits the passage 13 to be closed or opened, as 70 desired. The tube 20, through which the gas to be used for lighting purposes escapes, is closed at its lower end by a screwed plug or stopper 25; through which passes a siphon-pipe 26 to permit water carried over by the 75 gas to drain off and to collect at the bottom of the tube 20. Said water will be removed when required by removing the plug 25. The chamber 18 likewise carries a bent pipe 27, provided with a boss or ferrule 28 to receive a rubber tube and with a cock 29. This pipe 27 is in direct communication with the tube 20. The chamber 18 is furthermore furnished with a tubular extension 30, in which is a valve 32, kept on its seat by a 80 spring 33 of suitable strength. In the top of the tubular extension is an orifice 31. On the chamber 18, but traversing it without communicating with it, is another tube 34, which terminates at its upper end in a funnel-shaped mouth 35 and closed by a screw-stopper 36, having an orifice 37.

The entire arrangement or system thus described is located in a closed receptacle or vessel 38 of any suitable form, in which it is 95 supported by hooks or latches 39, held in position by tightening-bolts 40.

The working of the apparatus is as follows: After the vessel 1 has been charged with carbid of calcium up to a suitable point 100 the cover or lid is applied, thus forming a tight joint by means of the rubber ring 2. Then the block 10 is turned, so screwing the tube 8 into the socket 6 and tightening the ring 2 and effecting the closure. The plug or valve 24 is then applied to its seat by operating the milled button 23, and when this is done the whole is inserted in the vessel or receptacle 38, in which a predetermined quantity of water has previously been placed and 110 to which more may be added, if necessary, through the tube 34. The whole is then fixed

in place by means of the latches 39, and the apparatus is ready for working. If now the cock 29 and the valve 24 be opened, the water in the vessel 38 will pass through the orifice 9 into the vessel 1, wherein it will act on the carbide, so producing acetylene, which latter will drive out the air confined in the apparatus and take its place. From this moment there is a regular production of gas. If it be desired to discontinue it, the cock 29 must be closed. The acetylene gas continuing to generate increases the pressure in the vessel 1, and consequently the expulsion of the water is effected through the orifice 9 and the passage 13 into the vessel 38. By closing the plug or valve 24 the water is prevented from returning to the carbide. The grid or perforated plate 7 serves to prevent the carrying over of the carbide, which would detrimentally obstruct the tube 26. In case the tap 29 should have been closed and it has been forgotten to close the plug or valve 24, by operating the milled knob 23 the expulsion of the liquid will take place through the orifice 9 and the passage 13, as previously stated, after which if the action of the water on the carbide continues, for there is always a little water at the bottom of the vessel 1, the gas which will continue to generate will flow through the tube 41 and will collect in the chamber 18, where it will be able to attain a pressure determined by the spring 33, after which it will escape through the orifice 31 into the atmosphere. In cases where under the same conditions any gas should escape through the orifice 9 and the passage 13 this gas will expand in the water in the vessel 38 and will escape into the atmosphere through

the orifice 37 in the plug 36, thus preventing any undue pressure in the vessel 38.

Having now described my invention, what I claim, and desire to secure by Letters Patent, is—

A portable apparatus for generating acetylene, said apparatus including the following elements: an external receptacle for the water, provided with a removable cover; an inner receptacle for the carbide of calcium, closed by means of an air-tight cover; a central passage at the bottom of the inner receptacle; an adjustable plug for closing or opening said passage; a central tube above said passage, provided with a lateral opening for the water coming from the external into the internal receptacle; a siphon arrangement on the cover of the inner receptacle acting as a conveyer from the gas-generator to the drier; a tube receiving said arrangement, and communicating with the apparatus to be fed with gas; an external tube insuring said communication and provided with a tap for arresting or permitting said exit; a protecting perforated plate for preventing the carrying over of the carbide or the lime; a compression-chamber at the top of the external receptacle; a tube joining said chamber with the top of the inner receptacle, and provided with a safety-valve established on the cover of the external receptacle.

In testimony whereof I have signed my name to this specification in the presence of two subscribing witnesses.

CHARLES BILLY.
